STOVE

Clement Ehret, White Plains, N. Y.

Application April 23, 1938, Serial No. 203,760

8 Claims. (Cl. 219—19)

This invention relates to stoves and is directed more particularly to kitchen stoves for domestic use, the structure being such as to permit of raising and lowering movement of the stove body with respect to a normally stationary base, and to also provide for relative rotation of the various parts of the stove with respect to such base.

The present stove provides for a stationary base with a rotatably and vertically adjustable stove body having a relatively rotatable stove top. These various movements and adjustments may be accomplished without interfering with the feed of fuel to the burners or heating elements of the oven or stove top. The heating elements or burners may be supplied with a heating medium of any kind, such as gaseous or liquid fuel or electric current, as will be hereinafter more fully explained.

The object of the invention is to provide a stove which is extremely convenient to use and one which is perfectly safe in its operations.

Features of the invention, other than those adverted to, will be apparent from the hereinafter detailed description and claims, when read in conjunction with the accompanying drawings.

The drawings illustrate different practical embodiments of the invention, but the constructions therein shown, are to be understood as illustrative, only, and not as defining the limits of the invention.

Figure 1 shows a gas stove embodying the present invention with parts thereof in section and other parts thereof in elevation.

Figure 2 is a section on the line 2—2 of Figure 1.

Figure 3 is a view similar to Figure 1, but showing the invention as carried out in an electric stove.

Referring first to Figures 1 and 2, the stove is here shown as comprising a base 1 and a stove body 2. The base has an upstanding cylindrical portion 3 into which is telescopically received a stem 4. The stove body 2 has a centrally located depending cylindrical trunnion 5 rigid with the stove body and extending into the stem 4 to rotatably mount the stove body on the stem. The trunnion may, however, be locked to the stem against rotation by a set screw 6.

The stem 4 is provided at one side with an upright slot and in this slot is fixed a rack 7 rigid with the stem so as to move therewith. With this rack meshes a pinion 8 fixed on a shaft 9 which is supported for rotation in a housing 10 formed on the upstanding cylindrical portion 3 of the base

and forming therewith a closed chamber adapted to receive and house a lubricant.

Also fixed on the shaft 9 is a worm wheel 11 which meshes with a worm 12, journalled in the casing 10 and carried by an operating shaft 13. 5 This shaft extends out through the wall of the housing and is adapted to receive a crank, hand wheel or other suitable operating means, shown as a crank 14 in Figure 2.

It will be apparent that, as a result of this 10 construction, the rotation of the crank 14 will cause the stem 4 to be raised or lowered to any desired elevation or adjustment in order that the stove may be positioned at the most convenient height for the particular person who is to use it 15 and, when the crank is released, the worm will lock the worm wheel, so that the parts cannot inadvertently get out of position. In practice, the casing 10 may be packed with grease or other lubricating material, so that the parts will be 20 lubricated to operate without noise and without appreciable wear.

The stove body 2 may be of any desired shape and is provided with one or more ovens closed by appropriate doors 15. The upper part of the 25 stove body has anti-friction rollers 16 adapted to support a rotatable top 17 comprising a top plate 18 with an annular peripheral ring 19, the lower edge of which bears upon the anti-friction devices 16 to mount the top for rotation.

One or more braking devices are preferably secured on the stove body and are in the form of leaf springs 16' bearing against the under edge of the rotatable top ring 19 to exert a slight braking action thereon and thereby retard too rapid or 35 free rotation of the rotatable top.

The stove shown in Figure 1 is of the type adapted to burn liquid or gaseous fuel and is provided with burners or other heating elements 20 supported on a rotatable top and selectively fed 40 from an annular header 21 through individual control cocks 22. Fuel is fed to the header through a pipe 23 which is rigid with the header and extends radially inwardly to the axis of rotation of the stove body and is there connected 45 through a pivotal joint 24 to a pipe 25 which extends across the top of the oven, thence down the side and across the bottom of the stove body beneath the oven to the axis of the stove and there connects with an upright pipe 26. The pipe 50 extends downwardly and has a slip connection with an upright pipe 27 connecting with a horizontal pipe 28 leading out through the base to a source of gas supply. The pipe 26 has a sliding fit within the pipe 27 and suitable glands or pack- 55

ing may be associated with these two pipes to preclude leakage but to permit of relative rotation or coaxial sliding movement between them. At the upper end of the pipe 26 a branch pipe 29 leads to the oven burner 30 and the supply of gas thereto is controlled by a cock 31.

This arrangement allows the stove body to be raised and lowered and also rotated with respect to the base and also permits the rotatable top of 10 the stove body to be rotated with respect to the stove body, all without interfering with the supply of gas to the burners 20 or 30.

One or more of the anti-friction devices 16 is provided with a clamping handle 32, so that it can 15 be locked against rotation when it is desired to secure the rotary top against rotation relative to the stove. The set screw 6 provides for locking of the stove body against rotation with respect to the shank 4. The tie bolt 33 locks the rotatable 20 top to the stove body, so that it cannot be inadvertently lifted off.

The structure shown in Figure 3 is similar to that of Figures 1 and 2, but differs therefrom in that Figure 3 shows a stove wherein the heating 25 medium is electricity. The stove of Figure 3 has a base 1 with the upstanding cylindrical portion 3 and the telescoping shank 4 as before, these parts being vertically adjustable by the rack and pinion, worm and worm wheel connections described.

30 The stove body 2 has a rotatable stove top 17 adapted to be clamped against rotation by the locking handle 32 and said stove body has the depending trunnion 5 adapted to be locked against rotation when desired by the set screw 6.

35 However, it will be noted that the rotatable top has electric heating units or burners diagrammatically shown at 34, while the roasting and broiling oven has one or more heating units or burners, diagrammatically shown at 35. These 40 units and the wiring connections therefor are so associated as to permit of relative rotation of the several parts of the stove and also allow of vertical adjustment of the stove body. This is accomplished in the manner next to be described.

45 An electric feed cable 37 enters the base through an opening 36 and this cable is looped within the base to provide sufficient slack to allow of vertical adjustment of the stove body. The two wires 38 and 39 of the cable are separated and one passes upwardly through a central passage through the stem 4, in insulated relation thereto, and is connected to a center contact 40 fixed at the center of an insulating member 41. The other wire 39 passes upwardly 50 through an off center channel 42 and is connected to a conductor ring 43 concentric with the center contact 40 and insulated therefrom.

The trunnion 5 carries two spring pressed brushes 44 and 45, respectively, insulated from one 55 another and bearing against the contact 40 and the conductor ring 43, respectively, so as to permit the trunnion to rotate while maintaining the electrical connections. From the brushes 44 and 45, wires 46 and 47, respectively, lead to a coaxial contact 48 and a conductor ring 49 insulated from one another and positioned on the top of the stove body beneath the rotatable top. The rotatable top carries an insulating block 50 in which is supported a center brush 51 and an 60 off center brush 52 which two brushes respectively engage the contact 48 and the ring 49 and with these brushes the heating elements 34 are connected in multiple with control switches 53 included in the circuits, so that said elements can be individually controlled. Across the wires 46

and 47 is a shunt circuit 54 including the oven heating element or elements 35 and a control switch 55.

With this arrangement the rotatable top 17 is free to rotate with respect to the stove body and the stove body is free for rotation or vertical adjustment with respect to the base, all without interfering with the feed of electrical current to the respective burners.

It will thus be seen that in stoves of this invention, the top may be rotated while the body and base remain stationary, or the body and the top may be rotated collectively or the body may be rotated with the top remaining stationary, while in the position of fixed vertical adjustment 15 or during vertical adjustment. Furthermore the stove body may be vertically adjusted without concurrent rotation of either the body or the rotatable top thereof. Also the body may be locked with respect to the base by the set screw 6 and the top can be locked to the body by the handle 32.

In the accompanying drawings the vertical adjustment of the stove is carried out by novel mechanical means which permits of the raising and 25 lowering of the stove body with respect to the stationary base. However, this vertical adjustment may be accomplished hydraulically or pneumatically without departing from this invention.

I have hereinbefore referred to the stove body 30 as provided with an oven with which is associated suitable heating elements in the form of burners or resistance windings. I wish it understood that by reference to this oven, I mean to include either or both the roasting oven and a 35 broiling oven, or a combination thereof and that the heating elements associated therewith will be appropriate to the particular use of the oven.

Some of the subject matter disclosed in this 40 application is claimed in my copending application Serial No. 140,115.

Having thus fully described the invention, what I claim as new and desire to secure by Letters Patent is:

1. A stove comprising a base, a stove body rotatably supported on said base, a stove top rotatably supported on the stove body, an electric heating element supported on and carried by the stove top, electric current feeding lines extending through the base upwardly through the body to the heating element and provided with relatively rotatable coaxial current carrying contacts arranged between the base and the body and between the body and the stove top to permit of relative rotation between said base, body and top without disturbing heating medium current supply for said heating element.

2. A stove comprising a base, a stove body rotatably supported on the base, a stove top rotatably supported on said body, electric heating elements supported on and carried by the stove top, cooperating upper current carrying contacts carried by the stove top and by the stove body and yieldably engaging one another, the current carrying contacts of the stove top being electrically connected to the heating elements, additional cooperating lower current carrying contacts carried by the stove body and by the base and yieldably engaging one another with the lower contacts of the stove body electrically connected to the upper contacts of the stove body and the contacts of the base connected with a suitable source of current supply.

3. A stove comprising a base, a stove body rotatably supported on the base, a stove top rotat-

- 5 ably supported on said body, electric heating elements supported on and carried by the stove top, cooperating upper current carrying contacts carried by the stove top and by the stove body and yieldably engaging one another, the current carrying contacts of the stove top being electrically connected to the heating elements, additional cooperating lower current carrying contacts carried by the stove body and by the base and yield-
 10 ably engaging one another with the lower contacts of the stove body electrically connected to the upper contacts of the stove body and the contacts of the base connected with a suitable source of current supply, an oven in the stove body, an electric heating element for the oven, and electrical connections between the lower stove body contacts and the heating element of the oven.
4. A stove comprising a base, a stove body having an oven and supported on the base for rotation and vertical adjustment with respect thereto, a stove top rotatably supported on the stove body, an electric heating element supported on and carried by said stove top, an additional electric oven heating element supported on and carried by the stove body, electric heating medium supply connections extending from the base through the stove body to the heating elements of both the stove body and stove top and provided with relatively rotatable coaxial connections between the base and the body and between the body and the stove top to permit of relative rotation between said base, body and top without disturbing the feed of the electric heating medium, said connections being also provided, within the base, with a loop to permit of vertical adjustment of the stove body with respect to the base.
5. A stove comprising a base, a stove body having an oven and supported on the base for rotation and vertical adjustment with respect thereto, a stove top rotatably supported on the stove body, a heating element supported on and carried by the stove top, an additional oven heating element supported on and carried by the stove body, a heating medium supply conduit extending from the base through the stove body to the heating elements of both the stove body and the stove top and provided with relatively rotatable connections between the base and the body to permit of rotation of the body with respect to the base and with rotatable connections between the body and the stove top to permit of relative rotation between the top and the stove body without disturbing the heating medium supply.

elements of both the stove body and the stove top and provided with relatively rotatable and vertically extensible connections between the base and the body to permit of rotation and vertical adjustment of the body with respect to the base 5 and with rotatable connections between the body and stove top to permit of relative rotation between the top and the stove body without disturbing the heating medium supply.

6. A stove comprising a base, a stove body provided therein with an oven and rotatably supported on the base, means for locking the stove body against rotation relative to the base, an independently rotatable stove top externally of the oven and superimposed on the stove body, and other means for locking the stove top against rotation relative to the stove body.

7. A stove comprising a base, a stove body provided therein with an oven and rotatably supported on the base, means for locking the stove body against rotation relative to the base and in any desired angular position thereon, an independently rotatable stove top externally of the oven and superimposed on the stove body, and other means for locking the stove top against rotation relative to the stove body and in any desired angular position thereon.

8. A stove comprising a base, a stove body having an oven and supported on the base for rotation with respect thereto, a stove top rotatably supported on the stove body, a heating element supported on and carried by the stove top, an additional oven heating element supported on and carried by the stove body, a heating medium supply conduit extending from the base through the 35 stove body to the heating elements of both the stove body and the stove top and provided with relatively rotatable connections between the base and the body to permit of rotation of the body with respect to the base and with rotatable connections between the body and the stove top to 40 permit of relative rotation between the top and the stove body without disturbing the heating medium supply.

CLEMENT EHRET.
